Primary Examiner — Karen S Acker*(74) Attorney, Agent, or Firm* — George H. Leal**CLAIM**

The ornamental design for a sheet with pattern element for an absorbent article, as shown and described.

DESCRIPTION

FIG. 1 is a top view of a first embodiment of a sheet with pattern element for an absorbent article embodying the new design; and,

FIG. 2 is a top view of a second embodiment of a sheet with pattern element for an absorbent article embodying the new design.

The broken lines in the drawings depict the boundaries of the claim and form no part thereof.
